UNITED STATES PATENT OFFICE

JAMES H. PATRICK AND LEONARD H. PATRICK, OF SAN JOSE, CALIFORNIA

DOORSTOP

Application filed November 20, 1930. Serial No. 497,027.

This invention relates to door stops for garage doors, stable doors, barn doors and the like and the general object is to provide a very simple, cheap and convenient stop which is adapted to be mounted upon the inside face of the door and which when shifted to one position will drag on the ground or floor as the door is swung open and automatically brace the door against any inward swinging movement, thus holding the door open and which when the door is closed may be turned up into an inoperative position.

A further object is to provide a device of this character in which the stop proper is manually shiftable upon its supporting bracket or base into either its raised or lowered position and in which the stop proper is locked against bodily vertical movement when so shifted.

Other objects will appear in the course of the following description.

Our invention is illustrated in the accompanying drawings, wherein:

Figure 1 is a fragmentary edge elevation 25 of a door with our door holder applied thereto;

Figure 2 is a section on the line 2—2 of Figure 1;

Figure 3 is a fragmentary elevation showing the lower end of the brace or prop with a rubber tip thereon.

Referring to these drawings, 10 designates the base of our improved stop.

This base is formed with ears or otherwise so as to provide for the attachment of the base by means of screws 11 to a door A. This base on each side has a longitudinally extending slot 12. The lower end of this slot is angularly or inwardly extended as at 13. The upper end of this slot is also inwardly extended as at 14, the inward extension 14 extending to the inner face of the base. This inward extension 14 of the slot 12 is preferably slightly inclined forward and downward, though we do not wish to be limited to this, so as to permit the pins 12 to readily enter the portion 14. This inclination, however, is not great enough to permit the pin to slide down the slot under the weight of the brace.

The stop proper is designated generally 15. It is preferably hollow except for the two side walls and the web 16. The rear end is forked by cutting away the web 16 and the inner faces of the side walls are provided with inwardly extending studs or pins 17 engaged in the slots 12. If this stop is to be used on an inside door, as for instance on a house door, it is preferably provided at its lower end with a rubber foot 18. For barn doors or garage doors, such a rubber foot is not necessary.

In the operation of this device, the pins 17 are inserted into the slots 12 through the extensions 14 of the slots. The base is attached to the face of the door, thus closing the extensions 14 and thus preventing the detachment of the brace or stop proper 15. When the stop is not in use, the brace 15 will be raised to its full extent and then the upper end of the brace shifted rearward so as to carry the pins 17 into the extension 14, thus holding the brace from downward movement upon the base. If it be desired to use the stop, as for instance, when the door is about to be opened, the upper end of the brace is shifted outward to carry the pins into the slots 12 and the brace then drops down. As the door swings open, the brace will take an inclined position and the lower end of it will ride over the floor or ground.

The brace will drop down sufficiently so that the pins will enter the extension slots 13 and then if the reverse pressure comes upon the stop or brace 15, the pins in the extensions 13 will prevent any upward movement of the brace relative to the base and the base will hold the door to the extent to which it has been opened. When it is desired to release the door so as to close it, the upper end of the brace 15 is drawn outward until the pins reach the slots 12. Then the brace may be lifted until the pins are disposed within the slots 14, thus locking the stop in its raised position.

We do not wish to be limited to any particular means for forming this door stop. The structure might be made of wood or of cast metal or of sheet metal or of any other suitable material. It will be seen that the

device is very simple, may be cheaply made, is easily assembled and applied, and is thoroughly effective for the purpose intended.

We claim:—

5 A door holder of the character described, comprising a base having means whereby it may be attached to the inside face of a door, the base being formed on each of its side faces with a longitudinally extending slot, the upper end of each slot having an angular extension extending to the inner face of the base and the lower end having an inwardly extending angular extension, and a brace coacting with the base, the brace being forked at 10 its upper end to embrace the slotted portion of the base, the fork having inwardly extending pins engageable in said slots.

15 In testimony whereof we hereunto affix our signatures.

20 JAMES H. PATRICK.
LEONARD H. PATRICK.
